COLLAPSIBLE BED

Donald E. Green, 7322 Baker Ave. NE.,
Minneapolis, Minn. 55432

Filed Aug. 1, 1968, Ser. No. 12,993

Term of patent 7 years

Int. Cl. D6—01

U.S. Cl. D5—4

FIG. 1

FIG. 2

FIG. 3

FIG. 4

FIG. 1 is a view in top plan of a collapsible bed showing my new design;

FIG. 2 is a view in bottom plan thereof;

FIG. 3 is a view in side elevation thereof, the side opposite that shown being substantially a mirror image;

FIG. 4 is a view in end elevation thereof, the end opposite that shown being substantially a mirror image; and

FIG. 5 is a view in perspective thereof.

I claim:

The ornamental design for a collapsible bed, substantially as shown and described.
